FASTENING DEVICE

Frederick Kohnle, Dayton, Ohio, assignor to The
Monarch Marking System Company, Dayton,
Ohio, a corporation of Ohio

Application January 29, 1940, Serial No. 316,155

1 Claim. (Cl. 85—32)

This invention relates to mechanisms for attaching parts or units together and is particularly directed to a device for use in fastening units or parts together which units or parts are adapted to be easily detached or disassembled in normal usage. In fastening together units of this character the usual practice is to use some extraneous and completely removable part such as a nut or a screw. The difficulty with this type of fastening means is that it is very often misplaced or lost, requires special attaching tools and, a certain amount of manipulation in order to get the fastening parts in position for attachment.

It is the broad object of the present inventor to provide an attaching device which is carried by the part or unit to be attached or the part to which the attaching is done as a permanent part, that is, which is not removable. Accordingly, the device has the distinct advantage that the fastening elements are always available.

Furthermore, it has been the object of the present inventor to provide a device of this character which includes means for piloting the fastening device into position for the act of attachment and which is conveniently manipulated by hand without the use of tools for attachment or detachment.

Other objects and certain advantages will be more fully apparent from the description of the drawing in which:

Figure 1 is a perspective view of a unit or piece of mechanism carrying the device of the invention and adapted to be attached by means of it.

Figure 2 is a sectional view taken on line 2—2, Figure 1 showing the attaching device in position as carried by the unit after detachment.

Figure 3 is a sectional view taken similar to Figure 2 showing the attaching device in position fastening the unit in its normal position.

Referring to the drawing, the device concerned in this invention is generally indicated at 5. For the purpose of illustration, it is shown in use on a price marking machine. More specifically it forms a part of an inking unit generally shown at 6 and is adapted to hold the inking unit in position disposing its ribbon 7 over a platen or pad 8. Extending from the frame supporting the pad 8, is a supporting ledge 9. The plate element 10, which carries part of the supporting means for the ribbon 7, includes a horizontal flange or ear 11 adapted to rest upon the supporting ledge 9 and to be attached thereto. A stud 12 is fixed to the supporting ledge 9 as an integral part thereof. This stud extends up-

wardly and is adapted to traverse the horizontal portion 11 into engagement with the attaching device 5.

The horizontal flange 11 includes an aperture 13 and a countersunk marginal portion 14 surrounding the aperture. The fastening device includes a tubular retainer 15 fixed upon the horizontal portion or ear 11 of the ribbon bracket. Attachment of the sleeve to the ear is permanent and is accomplished by means of a sleeve portion 16 traversing the opening 13 and flanged over as at 17 within the countersunk portion of the opening. Thus the bottom surface of the supporting flange 11 is perfectly flat and lies flush with the top of the ledge 9.

A locking nut 18 of extended form is disposed in the bore 19 of the tubular retainer. The upper end of the nut is knurled as at 20 to provide a conveniently manipulated head for the nut. The nut includes a screw threaded bore 21 extending axially into its lower end which screw threaded bore is adapted to be engaged by the stud 12.

A cross pin 22 in the tubular retainer extends tangentially across the bore of the tubular element within an annular groove 23 in the nut. The groove is of sufficient length axially of the bore to permit movement of the nut along the bore of the retainer in the fastening and unfastening operation while the pin prevents displacement. A clamping washer 24 is disposed between the base of the nut and the base of the bore of the tubular retainer.

That portion of the bore of the retainer indicated at 25 is large enough to permit free insertion of the screw and the same is true of the clamping washer. The mouth of the screw threaded bore and the nut is flared as indicated at 26. The screw threaded bore 21 extends far enough into the nut so that the screw will not engage the bottom of the bore.

Thus, the retaining element prevents withdrawal of the nut and yet permits free rotative movement and appropriate longitudinal or axial movement. The nut provides a head of sufficient size to permit a good grip and the nut therefore may be manually screwed tightly into position. Since the bore entering the base of the retainer provides for free entrance of the screw, the device is easily piloted into position for screw threaded attachment.

Having described my invention, I claim:

A fastening device for attaching two elements together, said device comprising a screw threaded stud extending from and fixed to one element to be attached, a tubular retaining element fixed on

the other element to be attached, the bore of said tubular retaining element including a shoulder, said screw threaded stud extending into said bore beyond said shoulder, said tubular retaining element including a portion extending axially from and adjacent the shoulder, said other element to be attached including a countersunk portion, said portion extending axially from the tubular retaining element and being swaged into said countersunk portion and thereby presenting a flush surface in conjunction with said last mentioned

element to be attached when held against the other element to be attached, the shoulder of said countersunk portion lying against the underside of the shoulder of the tubular retaining element, 5 a thrust washer lying against the upper side of the shoulder, a nut rotatably mounted within the tubular retaining element and engaged on the screw threaded stud and against the washer, and means for maintaining said nut against axial displacement from the tubular retaining element.

FREDERICK KOHNLE.
